UNITED STATES PATENT OFFICE.

LEONARD MACOMBER, OF BOSTON, MASSACHUSETTS; DOROTHEA F. MACOMBER
ADMINISTRATRIX OF SAID LEONARD MACOMBER, DECEASED.

FINGER-NAIL BUFFER.

1,152,330.

Specification of Letters Patent. Patented Aug. 31, 1915.

Application filed June 4, 1914. Serial No. 842,925.

To all whom it may concern:

Be it known that I, LEONARD MACOMBER, a citizen of the United States, and resident of Boston, in the county of Suffolk and State of Massachusetts, have invented certain new and useful Improvements in Finger-Nail Buffers, of which the following is a specification.

This invention relates to finger-nail buffers and consists in the several improvements hereinafter described and claimed and illustrated by the accompanying drawings.

On the drawings: Figure 1 represents a side elevation of a buffer embodying my invention: Fig. 2 represents a top plan view of the buffer. Fig. 3 represents a longitudinal section of the same. Fig. 4 represents an inverted plan view of the base of the buffer. Fig. 5 represents a transverse section as indicated by line 5-5 of Fig. 3. In Fig. 5, however, the parts are slightly separated in order to show the mode of assembling.

The same reference characters indicate the same parts wherever they occur.

The structure as shown comprises a hard rigid base member 10, a soft cushioning element 11, a clamping ring 12, a cover plate 13, a handle 14, and clamping devices in the form of screws indicated at 15, 15. The base 10 and cushioning element 11 in conjunction with each other constitute the core or forming element which determines the contour of the attached sheet of flexible buffering material. The base 10 is formed with a laterally extending marginal flange 10' which coacts with an inwardly extending flange 12' formed upon the clamping ring 12, these two flanges coacting to clamp the marginal portion of a sheet of suitable buffering material 16, such as chamois skin. The term "ring" as used in this specification is not intended to imply a circular shape but is intended to imply continuous, endless formation, the clamping member 12 designated by the term "ring" being formed and arranged to surround the base 10. The ring 12 is provided with tapped holes 17 to receive the shanks of the clamping screws 15. These screws extend loosely through the cover plate 13 and their heads act upon the cover plate to draw the cover plate and clamping ring toward each other when the screws are set up tightly. The cushioning element 11 may be made of any suitable soft

material, such for example as sponge rubber, and it is fastened to the base 10. In the present instance I have not shown any fastening means but have relied upon glue to hold the contacting faces of the base and cushioning element in the relation shown.

The structure as shown and described is designed to facilitate the renewal of the buffering material 16. In order to attach a sheet of buffering material, the screws 15 are removed and the ring 12 and cover plate 13 are detached from the base. When the sheet of buffering material has been placed between the working surface of the cushioning element and the detached ring, onward movement of the ring places the marginal portion of the buffering material so as to surround the flange 10' of the base. The flange 12' of the ring fits so closely that it draws the buffering material firmly against the cushioning element 11 when the ring is being moved to clamping position.

The ring may be held upwardly against the flange 10' with one hand while the fingers of the other hand draw the edge of the buffering material upwardly if it be desired to further tighten the buffering material. It is to be understood that, in order to work the buffering material tight against the cushioning element, the sheet of buffering material will be larger than what is shown and that the excess buffering material which will project above the flange 10' is to be trimmed, as with scissors, so that its edge will be substantially flush with the top surface of the base, as shown. After the buffering material has been trimmed as last stated, and while the clamping ring 12 is frictionally held in clamping position, the cover plate 13 may be set in place and the clamping screws 15 may then be inserted and set tightly. The flanges 10' and 12' are right-angular flanges, their surfaces being at right angles to each other, and they produce two right-angular bends in the buffering material. The buffering material, being firmly clamped against two right-angular edges, is more securely held than if it were engaged by only one edge. This is a very desirable feature of the structure, as it avoids the likelihood of the buffering material becoming loosened in consequence of its wiping action upon the finger nails.

As shown by Figs. 3 and 5, the top surface of the base 10 is above the top edge of the clamping ring. In consequence of this

arrangement, when the cover plate is set in place it bears upon the base member but not upon the upper surface of the clamping ring. This insures tight clamping action as between the flanges 10' and 12'. The marginal portion of the cover plate is turned downwardly to form a flange 13', which flange overlaps the marginal portion of the clamping ring and covers the gap between 10 the clamping ring and cover plate. This formation gives the cover plate and clamping ring the characteristic relation of telescoping members.

Another feature of the invention is the 15 contour of the working surface of the cushioning element 11. As shown by Fig. 3, this contour includes a series of wavelike formations. I am aware that nail buffers have hitherto been formed with a single-concaved 20 contour; but so far as I am aware this is the first instance of a nail buffer having a series 25 of wavelike formations. One advantage of providing a series of such formations is that the inclined surfaces of the buffering material are brought more frequently into contact with the side portions of the finger nail. In using my buffer it is not necessary to tilt the same from side to side, nor is it necessary to rock the finger nail undergoing treatment 30 in order to buff the side portions of the nail. A simple longitudinal reciprocating movement is sufficient to buff substantially 35 the entire surface of the nail. The series of protruding portions indicated at 18 produce a pulsating pressure upon the nail, which is desirable as it gives a massaging effect which is both pleasant and beneficial.

I claim:

1. A finger-nail buffer comprising coöperative clamping members one of which is formed to surround the other, said members having coactive laterally extending flanges arranged to clamp between them the marginal portion of a sheet of flexible buffering material, and means to draw one of said members relatively to the other to effect clamping action of said flanges.

2. A finger-nail buffer comprising coöperative clamping members one of which is formed to surround the other, said members having coactive laterally extending flanges arranged to clamp between them the marginal portion of a sheet of flexible buffering material, a cover plate adapted to be seated

upon the back of the inner one of said 55 clamping members, and screws connecting said cover plate and the outer one of said clamping members, said screws being arranged to cause clamping action of said clamping members.

3. A finger-nail buffer comprising coöperative clamping members one of which is formed to surround the other, said members having coactive laterally extending flanges arranged to clamp between them the marginal portion of a sheet of flexible buffering material, a cover plate adapted to be seated upon the back of the inner one of said 60 clamping members, and screws connecting said cover plate and the outer one of said clamping members, said screws being arranged to cause clamping action of said 65 clamping members, said cover plate having a downwardly extending flange arranged to surround said outer one of said clamping members.

4. A finger-nail buffer comprising a base having an external laterally extending flange, a ring adapted to surround said flange and having an internal laterally extending flange adapted to underlie said flange of the base, the confronting laterally extending surfaces of said flanges being adapted to coact to clamp the marginal portion of a covering of flexible buffering material, said base and ring having surfaces arranged to bend said covering over the edges of both of said flanges, and means coacting with said base and ring to cause 80 clamping stress by said flanges.

5. A device of the character described comprising a working member having an undulatory working surface, and coöperative elements carried by said member and arranged to grip the marginal portion of a 95 sheet of flexible buffering material to hold such buffering material upon said working surface, said gripping elements being arranged to permit such buffering material to be drawn therebetween to conform to said undulatory working surface while said gripping elements are holding such material.

In testimony whereof I have affixed my signature, in presence of two witnesses.

LEONARD MACOMBER.
